UNITED STATES PATENT OFFICE

156,727

ARTICULATED SIGHT-SEEING VEHICLE

William D. Graham, San Leandro, Calif.

Application December 27, 1947, Serial No. 143,379

Term of patent 3½ years

(Cl. D14—3)

To all whom it may concern:

Be it known that I, William D. Graham, a citizen of the United States, residing at San Leandro, Alameda County, State of California, have invented a new, original, and ornamental Design for an Articulated Sight-Seeing Vehicle, of which the following is a specification, reference being had to the accompanying drawings, which form a part thereof.

Figure 1 is a perspective view of the articulated sight-seeing vehicle.

Figure 2 is a side elevation of the vehicle showing one side thereof, the other side of the vehicle is identical except for inclusion of a door just to the rear of the windshield.

Figure 3 is a plan view of the vehicle from which it will be apparent that the rear end of

the vehicle includes a merely conventional terminal end.

Figure 4 is a front elevation of the vehicle.

I claim:

The ornamental design for an articulated sight-seeing vehicle, as shown and described.

WILLIAM D. GRAHAM.
